C. J. DEL' MARMOL.
PILE CUTTER FOR LOOMS.
APPLICATION FILED DEC. 13, 1919.

1,368,551.

Patented Feb. 15, 1921.

WITNESS:

Alfred J. Bratton

INVENTOR.

Charles J. del Marmol
BY

Victor J. Evans ATTORNEY.

UNITED STATES PATENT OFFICE.

CHARLES J. DEL'MARMOL, OF FRANKFORD, PENNSYLVANIA.

PILE-CUTTER FOR LOOMS.

1,368,551.

Specification of Letters Patent. Patented Feb. 15, 1921.

Application filed December 13, 1919. Serial No. 344,654.

To all whom it may concern:

Be it known that I, CHARLES J. DEL'MARMOL, a citizen of the United States, residing at Frankford, in the county of Philadelphia and State of Pennsylvania, have invented 5 new and useful Improvements in Pile-Cutters for Looms, of which the following is a specification.

This invention relates to pile-cutters for 10 looms producing pile fabrics and it has for its main object to provide a pile-loop forming and rotary cutter attachment which is adapted for association with any standard type of loom.

15 A further object of this invention is to furnish a rotary pile-cutter the cutting members whereof are mounted in spaced relation and are operated to always cut the pile loops directly central so that an even 20 pile is insured for the length of the weave.

25 A still further object of this invention is to provide a guard in conjunction with each individual cutting member which is so fashioned to effectively prevent the accidental cutting of the weave while at the same time it divides or spreads the cut pile so that ease 30 in production is greatly increased.

With the foregoing and other objects in 35 view, my invention consists essentially of a rotary mandrel having a series of spaced disk cutters mounted thereon in combination with a corresponding series of guard members serving to separate the cut pile, said guard members having associated therewith the pile loop forming wires.

In the further disclosure of the invention 40 reference is to be had to the annexed sheet of explanatory drawings constituting a part of this specification, and in which like characters of reference designate the same or similar parts in all the views.

Figure 1— is a sectional end elevation of 45 my improved pile cutter, loop former, and the associated parts of a pile fabric producing loom, only such parts being illustrated as will enable those skilled in the art to which the invention appertains to get a clear understanding thereof.

Fig. 2— is a fragmentary plan of the 50 same.

Fig. 3— is an enlarged broken detail of the rotary cutter proper and mandrel; and

Fig. 4— is a perspective view of one of

the guard elements hereinafter more specifically described.

55 Referring to the drawings, the numeral 10, designates the loom harness and behind which there is securely mounted across the loom—not shown—a bar or roller 11 over which lengths of wire are folded and the 60 ends connected to constitute bands or wires 12, said wires 12 being weighted by weights 13 suspended therefrom by pulleys 14. These wires 12, are passed through the usual 65 eyes 15 in the harness 10 and are conducted over the breast beam 16 and threaded through eyes 17, in the ends of guard elements 18 hereinafter fully described. Sup- 70 ported in spaced relation to the harness 10 are pedestals 19, provided with upper and lower bearings 20, 21, respectively and freely 75 rotatable in the latter there is mounted a shaft or roller 22, over which the cut pile fabric feeds down to the cloth drum 23. Supported in the upper bearings 20, is a 80 mandrel 24, of a length to extend completely across the width of the fabric to be produced and threaded on said mandrel 24, are disk cutters 25, spaced apart by washers 26, a collar 27 and lock nuts 28 being provided 85 for securely clamping the cutters in proper spaced relation.

Clamped to the outer flanges of the afore- 90 said pedestals 19, by set screws or bolts 29, is a transversely disposed bar 30, rectangular 85 in cross-section and which is grooved at its lower edge 31, and provided with vertical serrations 32 on its front and rear faces, said serrations or grooves 32 being spaced apart to conform to the spacing of the pile loops 95 and cutters 25. This bar 30, serves to support the guards 18, above referred to, and each of said guards consists of a thin metal stamping provided with a cut out part 33, adapted to fit snugly on the bar 30 and to 100 seat in one of the rear vertical serrations 32, a heel 34 engaging in the groove 31. A thin sheet metal key 35 is passed through parallel cuts 36, and engages in the opposed adjoining vertical serration or groove thereby securely locking each guard 18 to the bar 30. It is to be here noted that each guard 18, is formed at one side with an upstanding lip or flange 37, so that when placed in position the alining cutter 25 lies between the cut 105 away or downwardly curved main wall 38

of the guard and the flange 37, slightly to the rear of the tongue portion 39, in which is the eye 17 through which passes the endless wire 12. The lay is designated by the 5 numeral 40, and 41 indicates the reed, while 42, 43, are fast and loose pulleys on the mandrel 24 for a belt drive—not shown.

From the foregoing it will be readily seen that as the pile loops 44 are formed on the 10 wires 12 and the weft beaten up by the reed 41 the produced material 45 is fed over the breast beam 16 to the tongues 39 which enter the pile loops, and as said material 45 travels forward the rotary cutters 25, cut 15 the pile loops 44 centrally while the flange 37 and cut away wall 38 of the guards 18, serve as spreaders for the pile. Furthermore it will be clearly seen that the lower edge of the cutter 25 is effectively prevented 20 from cutting the weave inasmuch as said weave is traveled forwardly below the part 46 of the guards.

Still further it will be readily understood that the number of cutters 25 will conform 25 to the number of pile loops 44 in the weft of the fabric and that each individual cutter is provided with an alined guard 18, while those skilled in the art to which my invention appertains will readily understand that 30 when the cutters become dulled or need changing or renewal for different types and width of fabric, such renewal or changing can be readily effected by removing the mandrel and substituting a fresh one, or changing 35 the cutters by first removing the lock-nuts 28. Further it will be conceded that I provide a cutting mechanism coöperating with spacing guards and pile-loop forming wires which is extremely efficient in use and 40 which at the same time prevents any damage to, or cutting of, the actual weave.

While I have described one practical embodiment of my invention, it will be evident that changes and modifications thereof 45 can be made without departing from its spirit and scope as set forth by the appended claims, and I wish it clearly understood that I do limit myself to the precise details shown and described.

50 Having described my invention what I

claim as new and desire to secure by Letters Patent, is:—

1. A pile loop-forming and cutting attachment for pile fabric looms comprising spaced bearings, a rotary mandrel mounted 55 in said bearings, circular cutting disks and spacing washers threaded on said mandrel, means for clamping said disks and washers firmly in place, a rectangular cross section bar supported between said bearings and 60 provided with alined serrations on opposed faces thereof, a guard element associated with each cutting disk and formed with a substantially U-shaped portion and laterally projecting eyed tongue and a cut out portion adapted to seat on the aforesaid bar in one of the serrations, means for locking each said guard element to the bar, longitudinally extending wires threaded through the eyed tongues and the loom harness whereby the 70 pile loops are formed, and means for keeping said wires taut.

2. A pile loop-forming and cutting attachment for pile fabric looms comprising spaced bearings, a rotary mandrel mounted 75 in said bearings, circular cutting disks and spacing washers threaded on said mandrel, means for clamping said disks and washers firmly in place, a fabric feeding roller supported below and in juxtaposition to said 80 mandrel, a rectangular cross section bar supported by said bearings and provided with alined serrations on opposed faces thereof, a guard element associated with each cutting disk and formed with a sub- 85 stantially U-shaped portion and laterally projecting eyed tongue and a cut out portion adapted to seat on the aforesaid bar in one of the serrations, a key for passage through parallel slots in the guard element and engagement in an opposed serration of the bar whereby said guard is locked in alinement with its associated cutting disk, longitudinally extending wires threaded through the eyed tongues and the loom harness whereby 90 the pile loops are formed, and means for keeping said wires taut.

In testimony whereof I affix my signature.

CHARLES J. DEL'MARMOL.
